HIGHWAY GUARD FENCE

Edward A. Robertson, Western Springs, Ill., assignor to Clark J. Robertson, Brookfield, Ill.

Application June 7, 1937, Serial No. 146,725

12 Claims. (Cl. 256—13.1)

The present invention relates to simplified and improved types of highway or road guard fences for use adjacent roads or highways at curves or at dangerous locations along the road. The improved guard fence is of a hinge supported rail type adapted to prevent automobiles accidentally coming into contact therewith, from completely leaving the roadway or road shoulder at curves or other dangerous points along the right of way by having the hinge supported rail act as a cushioning means to absorb impact shocks to obviate accidents and to prevent and reduce damage to the vehicle.

It is an object of this invention to provide an improved type of highway guard fence wherein supporting posts have a guard rail hingedly supported thereon, first allowing the rail supporting hinge members to act as a take-up means when vehicles strike the guard rail and then allowing the hinge members of the fence to serve as shock absorbers.

Another object of the invention is the construction of a highway guard fence wherein a continuous guard rail is mounted to be normally free from tension by the use of a hinge supporting connection between the continuous guard rail and the fence posts.

It is a further object of this invention to provide a road guard fence including hinge supports between the fence posts and a continuous rail to provide a construction wherein the rail is free to move to compensate for the expansion and the contraction of the rail metal due to temperature changes.

Another object of the invention is the construction of a highway guard fence wherein a continuous rail is mounted without tension in front of intermediate posts and between end posts by means of coil hinges, which upon impact of a vehicle with the fence, first act as hinged means to take up play and then serve as shock absorbers.

It is, furthermore, an object of this invention to provide an improved type of highway guard fence wherein the rail, constructed out of rail plates, rail bars or cables, is supported in position free from tension upon fence posts by means of hinge coil units to provide a construction wherein the rail, when contacted by a vehicle, carries the force to the hinge coil units which act to first take up the play and then act as shock absorbers.

Still another object of the invention is the provision of a road guard fence wherein a continuous rail is supported on spaced posts by means of hinge units, and wherein the ends of the rail are positioned to slidably project through end posts

permitting longitudinal shifting movement of the rail caused by the same being struck by a moving vehicle or caused by the contraction or the expansion of the rail material due to temperature changes.

It is an important object of this invention to provide an improved and simplified form of road or highway guard fence adapted to be mounted on the shoulder of a road at dangerous locations or at curves in the road, said guard fence including spaced posts and a continuous rail free from tension connected together by improved hinge units each consisting of apertured angle bars or the like which are laced or connected together by means of a heavy coil vertically disposed and spirally threaded through the apertured angle bars to serve as a hinge connection between a fence post and the fence rail, thereby producing an arrangement wherein the coils act as hinge means until all the play is taken up and then serve as shock absorbers when a vehicle leaves the highway and accidentally strikes the guard fence.

Other and further important objects of this invention will be apparent from the disclosure in the specification and the drawings.

The invention (in preferred forms) is illustrated in the drawings and hereinafter more fully described.

On the drawings:

Figure 1 is a fragmentary top plan view of a highway guard fence embodying the principles of this invention.

Figure 2 is a fragmentary front elevational view of the guard fence.

Figure 3 is an enlarged vertical sectional view taken on line III—III of Figure 2.

Figure 4 is an enlarged top plan view of the post mechanism illustrated in Figure 3 illustrating the hinge coil in its normal position in full lines and furthermore illustrating in dotted lines the hinge movement of the coil caused by the longitudinal movement of the fence rail.

Figure 5 is a fragmentary sectional detail taken on line V—V of Figure 3.

Figure 6 is a fragmentary detail view taken on line VI—VI of Figure 3.

Figure 7 is a fragmentary front elevational view of a modified form of guard fence using spaced rail cables or wires to form the fence rail.

Figure 8 is an enlarged top plan view of one of the end post constructions of the fence illustrated in Figure 1.

Figure 9 is an enlarged fragmentary horizontal detail section taken on line IX—IX of Figure 3.

Figure 10 is a top plan view of a modified form of end post construction for the guard fence when the fence rail is disposed longitudinally between the end posts and wherein the normal position of the hinge coil and the fence rail are illustrated in full line while the operation of said members is illustrated in dotted lines.

Figure 11 is a fragmentary side elevational view of the end post construction illustrated in Figure 10.

Figure 12 is a fragmentary top plan view of another modified form of end post construction wherein the end of the guard rail slidably projects through the end post between upper and lower reinforcing metal bands engaged on the post.

Figure 13 is an elevational view of the modified form of end post shown in Figure 12.

As shown in the drawings:

The reference numeral 1 indicates the shoulder 20 of a concrete highway. Constructed upon the shoulder 1 of the road adjacent the side of the highway is an improved guard fence adapted to be located at selected dangerous locations along the road or at road curves. The improved highway guard fence is provided for the purpose of reducing the seriousness of accidents when vehicles are accidentally run off of the road and plunge into contact with the guard fence. The improved highway guard rail when struck by a moving vehicle acts as a means for reducing the seriousness of the accident by absorbing the shock in the rail member and in the supports for said rail member which supporting units are of a hinge coil construction and act as hinges until all 35 the play is taken up after which the hinge coils act as shock absorbers.

In the form of highway guard fence illustrated in Figures 1 to 6 and in Figures 8 and 9 the fence comprises a plurality of spaced posts 2 each having rigidly secured thereon a hinge supporting unit for hingedly supporting a continuous rail mechanism in position free from tension.

Each of the hinge supporting units comprises a post angle iron consisting of a mounting flange 45 3 having apertures therein for the reception of mounting bolts 4 which project through the flange 3 and through the posts as clearly illustrated in Figure 3. Integrally formed at right angles to the angle flange 3 is an angle flange 5 provided with a row of apertures 6. Positioned opposite the post angle iron is a rail angle iron consisting of a mounting flange 7 and a flange 8 integrally connected therewith at right angles. The post and rail angle irons of each hinge unit are 55 mounted in reverse relation with respect to one another and diagonally opposite as illustrated in Figure 4 to position the flanges 5 and 8 substantially opposite one another. The flange 8 of the rail angle iron is provided with a row of 60 spaced apertures 9 which are staggered with respect to the apertures 6 in the post angle iron 5 as shown in Figure 3, for the reception of a heavy hinge coil 10 which is of a spiral construction and is adapted to be screwed or threaded downwardly through the openings 6 and 9 to connect the angle irons. The lower end of the hinge coil is threaded downwardly until the end contacts the bottom portion of the angle flange 7 which acts as a stop to limit the downward 65 movement of the hinge coil. The upper end of the hinge coil is bent downwardly to form a stop finger or hook 11 which is spaced a short distance from the flange 5 when the hinge coil is in its proper or lowermost position, as shown in Figures 5 and 6.

The hinge units supported on the fence posts afford a means for supporting a rail unit free from tension. The rail unit is of a continuous construction comprising a plurality of rail plates or strips 12 constructed of sheet steel and arranged end to end in overlapping relation with the overlapping ends rigidly secured to the rail supporting flanges 1 by means of rivets 13 or other suitable means. The rail strips or plates 12 are thus rigidly connected one to another to form a continuous rail member which is supported by the angle members 1-8.

In the fence construction illustrated in Figures 1 and 2 it will be seen that the fence rail is free to move longitudinally with the contraction or the expansion of the fence rail material due to temperature changes. The fence rail member, being of continuous construction, is mounted so that it is not under tension. The angle members 1-8 which connect the continuous rail with the hinge coils 10 permit a longitudinal shifting movement of the continuous rail due to the hinge action of the coils between the rail and the fence posts. When an automobile accidentally leaves the road and strikes the guard fence, the rail plates or strips 12 being resilient receive the shock and tend to transmit the same to the hinge coils which first act to swing or move with respect to the supporting flange members 5 of the post angle bars to take up the play 30 and then act as shock absorbers to absorb the impact shocks. The hinge movement of the rail supports is clearly illustrated in dotted lines in Figure 4 which figure indicates that the apertured flange 8 first will slide on the coil 10 in 35 one direction or the other and then will cause the coil to act as a hinge to swing into a dotted-line position depending on the direction from which the force may come.

The improved guard fence is of the shock absorbing type wherein hinge units connect the rail with the fence posts so that when automobiles strike the fence rail the shock is distributed throughout the members of the fence thereby reducing the seriousness of accidents.

While the form of road guard fence illustrated in Figures 1 and 2 discloses a guard rail constructed of strips of sheet steel, it will, of course, be understood that the rail may be constructed of other material such, for example, as wire cables 14 which are connected in spaced parallel relation as clearly illustrated in Figure 7 and are secured to the rail flanges 1 of the hinge units by means of staple bolts 15 or the like.

Referring to Figures 10 and 11, an end post construction is illustrated for use in a guard fence similar to that illustrated in Figures 1 and 2 but wherein the end rail plate 16 continue past the last intermediate fence posts 2. The outer end of end rail plate 16 is provided with a row of apertures 17 to permit the loops of an end hinge coil 18 to be threaded therethrough. The end hinge coil 18 is also threaded through openings 19 provided in one of the flanges of an end post angle iron 20 which is rigidly secured to an end post 21 by means of bolts 22.

In the modified form of fence construction using the end post support for the ends of the continuous rail as illustrated in Figures 10 and 11 both the hinge constructions of the intermediate post 2 and the end posts 21 act to support the continuous rail member in position free from normal tension and permit longitudinal shifting movement of the rail member when the same is accidentally impacted by automobiles or the like.

A fence construction is thus provided wherein the resiliency of the rail plates or strips first act to absorb part of the initial shock due to the impact after which the shock is distributed to the hinge coils 10 and 18 which act to take up any play in the rail and then act as shock absorbing mechanisms. With the shifting movement of the rail the intermediate hinge coils 10 will move into the dotted line positions of Figure 4 either to one side or the other depending upon the direction of the shock, while the end coils 18 tend to swing from the full-line position of Figure 10 into the dotted-line position to one side or into a similar dotted-line position on the opposite side 15 of the full-line position.

To compensate for the expansion and contraction of the rail member due to temperature changes, it has been arranged to mount the end rail 16 in the full-line position illustrated in Figure 10 a little to one side of the vertical axis of the end coil 18, so that upon contraction of the rail member the same may move from the full-line position of Figure 10 into the dotted-line position indicated by the reference numeral 23. In 25 case of the expansion of the rail member, the apertured end of the end rail plate 16 may slide on the coil 18 or cause the coil to swing from the full-line position of Figure 10 toward the dotted-line position.

30 Figures 12 and 13 illustrated another modified form of an arrangement for an end post construction for a guard fence combining the arrangement illustrated in Figures 1 and 2 but having end rail plates 24. Each of the end rail plates 24 is positioned so that the end portion thereof slidably projects through a slot 25 provided centrally in the upper end portion of an end post 26. In the showing of the slot in Figure 13, the slot extends from the top of the post downwardly for a selected distance depending upon the width of the end rail plate 24. To reinforce the slotted upper end of the end post 26 steel reinforcing bands or collars 27 are engaged around the post 26 in spaced relation as clearly illustrated in Figure 13 to permit the end portion of the end rail member 24 to slidably project through the post slot between the upper and lower bands 27.

With the improved end post construction illustrated in Figures 12 and 13, the continuous fence rail is adapted to move longitudinally in one direction or the other due to the impact of vehicles against the fence rail or due to the contraction or 55 the expansion of the rail member caused by temperature changes or the like.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A highway guard fence comprising a plurality of spaced posts, a continuous fence rail, and hinge coil units connecting the rail with said posts.

2. A road guard fence comprising a plurality of spaced posts, apertured angle members rigidly secured to said posts, a continuous rail, apertured angle members secured to said rail, and hinge coils threaded through the apertured angle members on said rail and on said posts for supporting the rail in position free from normal tension.

3. A highway guard fence comprising a plu-

rality of spaced posts, a continuous rail member, apertured supports on said posts and on said rail member, and upright coils pivotally engaging the supports on said posts and on said rail member to support the rail member in position free from tension for longitudinal movement transversely of the posts when the rail member is subjected to impact forces.

4. A highway guard fence comprising a plurality of spaced posts, a continuous rail unit, and hinge units supporting the rail unit on said posts, each of said hinge units comprising apertured supporting members one of which is rigidly secured to a post and the other of which is secured to the rail unit, and a hinge coil threaded through the apertured supporting members to connect the same and form a hinge support for the rail unit allowing longitudinal movement of the rail unit in either direction when impact forces are applied to the rail unit.

5. A highway guard fence comprising a rail unit, a plurality of supporting posts, and hinge units connecting the supporting posts with the rail unit, each of said hinge units comprising a pair of apertured angle members, means for rigidly securing one of the angle members to a fence post, means for rigidly securing the other of the angle members to the rail unit, and a hinge coil vertically disposed between the post and the rail unit and threaded through the apertures in the angle members.

6. A highway guard fence comprising a rail unit, a plurality of supporting posts, and hinge units connecting the supporting posts with the rail unit, each of said hinge units comprising a pair of apertured angle members, means for rigidly securing one of the angle members to a fence post, means for rigidly securing the other of the angle members to the rail unit, and a hinge coil vertically disposed between the post and the rail unit and threaded through the apertures in the angle members, said hinge coil having the lower end thereof contacting one of said angle members to limit the downward movement of said hinge coil with respect to said angle members, said coil having the upper end thereof deflected or hooked.

7. A highway guard unit comprising a pair of end posts, a rail unit disposed between the end posts, hinge coils connecting the ends of the rail units with the end posts, a plurality of intermediate posts disposed to one side of the rail unit, and hinge coils connecting the intermediate posts to said rail unit.

8. A highway guard fence comprising a pair of end posts, a continuous rail unit disposed between the end posts, said rail unit having the end margins thereof provided with apertures, apertured supports on the end posts, hinge coils threaded downwardly through the apertured supports and through the apertures in the ends of the rail unit, a plurality of spaced intermediate posts positioned adjacent one side of the rail unit, apertured supports secured to the intermediate posts and to the rail unit, and intermediate hinge coils threaded through the apertured supports on the intermediate posts and on the rail unit.

9. A highway guard fence comprising end posts and intermediate posts, a continuous rail unit disposed between the end posts and adjacent one side of the intermediate posts, and hinge coils mounted on the end posts and on the intermediate posts with the axes of said hinge coils disposed substantially parallel to the axes of said post, said hinge coils connected with the ends of the rail

unit and with the sides thereof for supporting the rail unit in position free from normal tension.

10. A highway guard fence comprising a pair of spaced slotted end posts, a rail unit disposed between the end posts with the ends of the rail unit slidably projecting through the slots in the end posts, a plurality of intermediate posts positioned to one side of the rail unit, and hinge coils connecting the intermediate posts with intermediate points along the length of the rail unit.

11. A highway guard fence comprising a pair of spaced slotted end posts, means for reinforcing the slotted end posts, a rail unit disposed between the end posts with the ends of the rail unit slidably projecting through the slots in the end posts,

a plurality of intermediate posts positioned to one side of the rail unit, and hinge coil units connecting the intermediate posts with intermediate portions of the rail unit to support the rail unit in position free from tension and longitudinally shiftable when subjected to impact stresses or temperature changes.

12. A highway guard fence comprising a pair of end posts, a rail unit shiftably mounted between the end posts, a plurality of intermediate posts mounted to one side of the rail unit and out of line with the end posts, and hinge coils connecting the rail unit at spaced points between the ends thereof with the intermediate posts.

EDWARD A. ROBERTSON. 15
